United States Patent Office

Des. 209,361
Patented Nov. 21, 1967

209,361

TOASTER OR THE LIKE

Earl E. Sutton, Mansfield, and Richard B. Hall, Akron, Ohio, assignors to Dominion Electric Corporation, a corporation of Ohio

Filed Jan. 13, 1967, Ser. No. 5,412

Term of patent 14 years

(Cl. D81—10)

Fig. 1

Fig. 2

Fig. 3

Fig. 4

FIGURE 1 is a perspective view of a toaster embodying our design;

The dominant features of our design are shown in full lines.

We claim:

The ornamental design for a toaster or the like, substantially as shown and described.
